UNITED STATES PATENT OFFICE.

MAURICE FRANK HUTCHISON, OF HERNDON, VIRGINIA.

VALVE.

1,132,095.

Specification of Letters Patent. Patented Mar. 16, 1915.

Application filed April 21, 1914. Serial No. 833,552.

To all whom it may concern:

Be it known that I, MAURICE FRANK HUTCHISON, a citizen of the United States, residing at Herndon, county of Fairfax, and 5 State of Virginia, have invented certain new and useful Improvements in Valves, of which the following is a full, clear, and exact specification.

This invention relates to valves especially 10 designed for use on steam, vapor, or other radiators for regulating or controlling the amount of heat emitted by each radiator to meet varying weather conditions. Such valves are used at the supply ends of the 15 radiators so as to control the amount of steam or vapor admitted to them.

One object of the present invention is to provide a valve which may be used on any size of radiator from the smallest to the 20 largest, thus avoiding the necessity of making and carrying in stock several sizes of valves to supply various sizes of radiators as heretofore. The present valve has such a wide range of adjustments that it is 25 capable of being set for supplying any desired amount of steam or vapor within the capacity of any of the ordinary sizes of radiators.

Another object is to provide adjustable 30 means for limiting the extent to which the valve may be opened, in order that said valve may be used on the smaller sizes of radiators without danger of an oversupply of steam or vapor being admitted thereto. At 35 the same time, when the maximum limit of supply has been fixed by said adjustable means the valve may be adjusted at will to any point between zero and said fixed maximum point in order to vary the amount 40 of heat emitted from the radiator to meet weather conditions as previously mentioned.

The invention will be first hereinafter described in connection with the accompanying drawings, which constitute a part of 45 this specification, and then more specifically defined in the claims at the end of the description.

In the accompanying drawings, wherein 50 similar reference characters are used to indicate corresponding parts throughout the several views Figure 1 is an elevation of a valve constructed in accordance with my invention, looking into one passage thereof; Fig. 2 is a central vertical section of Fig. 1; 55 Fig. 3 is a plan view of the valve, and Fig.

4 is a detailed view of the valve proper removed from its casing.

The valve casing A has two passages B and C arranged at an angle to each other and communicating by a slot D in the partition E within the casing. This partition constitutes part of the wall of the passage B which is tapered as illustrated in Fig. 2.

The valve proper F is cup-shaped and tapered to conform to the passage B in 65 which it is snugly fitted. The stem G of the valve extends through the casing and is fitted with a handle H. A spring K housed in a chamber L in the outer portion of the casing bears against the inner face of the 70 handle and tends to preserve the snug fit of the valve proper in the passage B. In the wall of the valve proper there is formed a tapering slot M having diverging edges extending around said valve. One edge of 75 the slot M is preferably arranged in the plane of one end of the slot D, and the greatest width of said slot M is preferably equal to the length of said slot D. The slot M preferably extends almost entirely around 80 the valve proper as clearly illustrated in Fig. 4, in order to permit of a wide scope of adjustment.

Arranged concentrically around the stem 85 of the valve is a circular scale P which is provided with a fixed stop Q and an adjustable stop R, the latter consisting of a bolt adapted to be clamped at any desired point in either one of two arcuate slots S extending almost entirely around the scale as 90 shown in Fig. 3. The handle H carries a finger or pointer T which is arranged opposite the zero point on the scale when in contact with the fixed stop.

In operation the movable stop R is ad- 95 justed on the scale opposite the point thereon which indicates the maximum capacity of the radiator to which the valve is applied. Thus if the maximum capacity of the radiator is 35 feet radiating surface, the 100 movable stop R is clamped at the point illustrated in Fig. 3, so as to limit the movement of the handle to the arc between the fixed stop Q and said movable stop R which in this case covers 35 points on the scale. 105 There is, therefore, no danger of the valve being opened too far, that is, so as to admit more steam or vapor to the radiator than its capacity justifies. It will be understood, of course, that when the finger T is at zero, 110

the slot D is entirely closed by the valve proper, that is to say by the uncut portion of the latter between the small and large ends of the slot M, which as illustrated in Fig. 4, is preferably equal to the width of said slot D. As the valve proper is turned by means of the handle so as to cause the pointer to move around the scale from the fixed stop toward the movable stop, an increasing proportion of the slot D is uncovered or opened, whereas movement of the valve in the opposite direction has the effect of gradually closing the slot D. It will thus be seen that while the valve may be regulated in advance to correspond to the capacity of any size radiator, said valve may afterward be turned off or on to any desired extent between the limits thus fixed for heating different proportions of the entire radiating surface of the radiator, and that such limited regulation may be effected just as readily as in an ordinary valve having fixed limits in both directions.

The scale indicating the capacity or length of radiating surface of radiators on which the valve may be used is intended to apply to a standard pressure, as two ounces. When used with a heating system having a different pressure, allowance for such difference can easily be made in setting the valve with respect to the scale. For instance, if there is a pressure of four ounces, and the radiator has a capacity of 40, the valve would be set at 20.

It will be noted that a slight space U is left between the top of the valve F and the partition V in the casing through which the valve stem G extends. A slight space W is also left between the scale plate P and the pointer T. These spaces permit the valve to be pressed down against the influence of the spring K to a slight extent for loosening said valve in case it becomes stuck by reason of corrosion or other cause. A washer X is placed around the valve stem above the spring and fitted in the upper end of the

chamber L to protect the spring and guide the valve stem.

Having thus described my invention, what I claim as new and desire to secure by Letters Patent of the United States is:

1. The combination with a casing having branch passages and a rectangular slot through which they communicate, of a valve provided with a tapering slot movable across the slot in the casing for varying the uncovered portion of said latter slot one edge of said tapering slot being level with one edge of said rectangular slot.

2. The combination with a casing having branch passages and a rectangular slot through which they communicate, of a valve having a tapering slot movable across the slot in the casing for varying the uncovered portion of the latter slot, a scale on the casing, a pointer attached to the valve and cooperating with the scale for indicating the position of the slot in the valve with respect to the slot in the casing, a fixed stop on the scale for engaging the pointer when the slot in the casing is closed, and an adjustable stop on the scale also adapted to be engaged by the pointer for limiting the opening of said slot in the casing beyond a predetermined extent.

3. The combination with a casing having branch passages, of a valve fitted in one passage and having a uniformly gradual substantially unbroken spiral edge arranged obliquely with respect to the other passage and extending from the lowest to the highest level thereof, and means for turning the valve to move its spiral edge across the latter passage, thereby uniformly varying the uncovered portion of said passage.

In testimony whereof I have signed my name to this specification in the presence of two attesting witnesses.

MAURICE FRANK HUTCHISON.
